APPARATUS FOR PRODUCING SAFETY
PAPER

William H. Grogan and Frank C. Ladd, Turners Falls, Mass., assignors to Keith Paper Company, Turners Falls, Mass., a corporation of Massachusetts

Application September 13, 1933, Serial No. 689,218

3 Claims. (Cl. 92—40)

This invention relates to an apparatus and a method for incorporating in a paper web bands of small tissue paper disks commercially known as planchets. These small disks when incorporated into the paper stock during its formation may be practically invisible as long as the paper is viewed in the ordinary manner by reflected light. They are, however, clearly visible by transmitted light. If any attempt is made to alter, by erasure or chemical means, writing which overiles these disks they will be rendered abnormally distinct and will make the fact of alteration clearly apparent.

One object of this invention is to provide an improved apparatus for forming commercially webs of paper having one or more lines of planchets incorporated in the body of the web during its formation. A further object is to provide an apparatus and a method for handling the planchets and depositing them on a partially formed web in such a manner as to insure substantially even distribution of the planchets and to provide for the incorporation of the planchets into the web with the planes of the individual disks all lying in the plane of the web. A further object is to provide a method and an apparatus for this general purpose in which a minimum of disturbance of the partially formed web will be created in the operation of applying the planchets. A further object is to provide a method and an apparatus by which the planchets will be embedded in the material of the web without causing any abrupt transition of character or of ordinary appearance in the web stock on either side of or in the planchet band. Additional objects will appear from the following description and claims.

Referring to the drawing:

Fig. 1 is a diagrammatic view of an apparatus constructed in accordance with our invention; 40 Fig. 2 is a detail plan view of a portion of the apparatus shown in Fig. 1; and

Fig. 3 is a detail elevation of one of the parts.

The present invention is preferably carried out by adding the planchets to the paper stock during the formation of a web upon the wire of a Fourdrinier machine. Since Fourdrinier machines are standard in the paper making art the Fourdrinier wire 10 has been indicated diagrammatically only. The paper stock out of which the web is formed flows onto the moving wire from a head box 11, and passes under a slice bar 12 by which irregularities in the thickness of the web are prevented. At a point preferably just beyond the slice bar a plurality of ducts or pipes 13 are provided, leading from a tank 14 extending across

the wire. These ducts 13 terminate at a point just above the partially formed web on the wire and are given such an inclination that the stock flowing from them travels when it meets the web with substantially the same speed as the latter. 5 As will be explained more fully below, the tank 14 is supplied with dilute stock in which a large number of planchets are intimately mixed. As the planchets are carried down the ducts 13 they encounter the as yet unmatted paper stock on 10 the wire 10 and become incorporated with it as the web becomes more and more compact in its travel along the wire.

In commercial practice we have found that a proper inter-mixture of the planchets with the 15 paper stock on the wire can be controlled by certain precautions in the manner of preparation of the stock mixture in which the planchets are floated and in the manner in which this stock mixture is handled during its passage from the 20 supply tanks to the surface of the partially formed web. In the first place, in order to avoid the formation of abrupt hinge lines in the paper web and to insure that the surface appearance of the planchets when embedded in the web will resemble the web itself rather than the paper out of 25 which the planchets were cut, it is necessary to have the stock mixture possess characteristics similar to that possessed by the stock out of which the web is formed. Practically this result can be 30 accomplished best by the use, as a floating medium for the planchets, of the so-called white water which drains from the Fourdrinier wire. Since the white water contains mainly short 35 fibers along with the chemicals which were present in the original stock and since the fiber content of the white water would be diminished by repeated passing through the wire, it is generally desirable to add from time to time a certain additional amount of short fibers to the white water 40 when it is used for this purpose.

In the drawing a tray 15 has been shown conventionally as collecting the white water from underneath the Fourdrinier wire. A pipe 16 connects this tray with a tank 17 from which the 45 white water is normally taken off for use in other parts of the paper making process by a pipe 18. We have provided an additional pipe 19 leading from the tank 17 to a pump 20 by which any desired quantity of the white water may be elevated 50 through a pipe 21. This latter pipe merges into two pipes 22 and 23 provided with valves 24 and 25 and leading into a pair of tanks 26 and 27. By opening the valves 24 and 25 alternately the two tanks can be filled in succession. Pipes 30 55

and 31 provided with valves 32 and 33 lead from the lower portions of these tanks into a common pipe 34 which is shown as being directed into a tank 35 at a lower level. A pipe 36 leading from this tank in its upper portion leads to a pump 37 by which excess material from the tank 35 may be returned to the pipe 21. By this means a constant head can be maintained in the tank 35 at the level chosen for the pipe 36.

10 One or more pipes 40, each having a regulating valve 41 located in it, lead from the tank 35 to the tank 14. It will be observed that with the system of piping described an adequate hydraulic head is maintained at all points to insure proper 15 delivery of the stock, but that the head is broken up so that the velocity of the stock will not be excessive at the time it reaches the wire. In particular the level in the tank 14 is preferably kept low and the tank itself is located not very 20 far above the surface of the wire 10. To still further reduce the velocity of the stock as it reaches the wire the ducts 13 are preferably made serpentine in form as is best shown in Fig. 2.

Provision is also preferably made for agitating 25 the planchet bearing stock in each of the tanks so that the planchets will be maintained in a substantially uniform state of suspension. For this purpose perforated pipes 45 are preferably located in the lower portions of each of the 30 tanks 26, 27, and 35, and are connected to a suitable compressed air supply. The bubbling of air through the tanks constantly agitates the stock so that any settling of the planchets is impossible. The capacity of the tank 14 is relatively 35 small so that direct agitation is generally unnecessary and is generally undesirable on account of the tendency towards uneven discharge which it produces. A sufficient degree of agitation for this tank is usually obtained by the constant 40 movement of the stock as it emerges from the pipe 40. In case a large number of bands of planchets are to be applied to the web it is desirable in order to secure uniform distribution that several pipes 40 be used spaced apart along 45 the length of the tank in accordance with the spacing of the pipes 13. The pipes 40 may, in that event, be provided with separate controlling valves to insure evenness of flow, and the tank 14 provided with partitions 46. In order to insure 50 an even flow of the planchet suspension from the pipes 40 to the final delivery ducts 13, the tank 14 is preferably provided with baffles 47 not quite reaching the bottom of the tank, through one of which the pipes 40 extend. The 55 delivery ducts 13 are bent upwardly as shown at 48, between the baffles. By this means a very even flow through the ducts 13 is obtained while preserving enough upward flow in the tank to keep the planchets always in suspension. The 60 ends of ducts 13, which are preferably in pipe form, may be beveled off as at 58 (Fig. 3) with the terminal portion preferably somewhat extended and flattened to form a delivery lip 51. The end portion of each pipe 13, or the lip 51 65 if used, is positioned close to the traveling partially formed web, preferably just clearing the still soft stock so that no disturbance of the latter will be produced.

It will be understood from the above descrip-

tion that the planchets are kept in a constant state of agitation in a stock mixture having sufficient correspondence to the stock on the wire so that no abrupt line is formed at the edges of the planchet bands. The planchets will automatically arrange themselves in the plane of the web as they glide down the plates 13, lying at first upon the top of the partially formed web, then becoming incorporated in it during its travel along the wire and during the further condensation of the web on the felts and between the press rolls. Any agitation due to the addition of the planchets and their carrying medium is substantially eliminated. The apparatus has been shown in diagrammatic form as the design of many of the specific units is not of importance. Changes in the structure and arrangement of the parts can obviously be made to adapt the invention to different installations without departing from the invention as described in the following claims. 20

We claim:

1. In an apparatus for incorporating planchets in a paper web during its formation upon a Fourdrinier wire, a collecting tank for white water, a pair of storage tanks, means for delivering 25 the white water from the collecting tank alternatively into one or the other of the storage tanks, a third storage tank, means for delivering the liquid from either of the first two storage tanks to the third storage tank, a pipe leading 30 from said third storage tank at an intermediate elevation thereof, means for delivering liquid from said pipe to the first two storage tanks to thereby preserve a constant level in the third storage tank, means for agitating the liquid in 35 each of the storage tanks, a delivering tank extending across a Fourdrinier wire, one or more ducts leading from said delivering tank in a sinuous path to a point above the partially formed web on the wire, and one or more pipes leading 40 from the third storage tank to said delivering tank.

2. An apparatus for incorporating planchets into a paper web during its formation on a Fourdrinier wire which comprises a tank, a pipe 45 extending upwardly to an intermediate elevation of said tank and leading to a point closely adjacent the paper stock on the wire, baffling means within the tank extending to a point below the opening to the pipe, and means for supplying to 50 said tank below the baffle planchets in a substantially uniform state of suspension and in regulable quantity.

3. An apparatus for incorporating planchets into a paper web during its formation on a 55 Fourdrinier wire which comprises a tank, a pipe extending upwardly to an intermediate elevation of said tank and leading to a point closely adjacent the paper stock on the wire, the end of the pipe adjacent the paper stock being cut 60 away to provide an open distributing portion from which the planchets flow onto the stock, baffling means within the tank extending to a point below the opening to the pipe, and means for supplying to said tank below the baffle 65 planchets in a substantially uniform state of suspension and in regulable quantity.
